UNITED STATES PATENT OFFICE.

GEORGE M. MEREDITH AND JAQUELIN M. MEREDITH, JR., OF NORFOLK,
VIRGINIA.

DESIGN FOR A HAT OR STICK PIN.

No. 38,126.

Specification for Design.

Patented July 10, 1906.

Application filed April 25, 1906. Serial No. 313,720. Term of patent 3½ years.

To all whom it may concern:

Be it known that we, GEORGE M. MEREDITH and JAQUELIN M. MEREDITH, Jr., citizens of the United States, residing at Norfolk, in the county of Norfolk and State of Virginia, have invented and produced a new, original, and ornamental Design for a Hat or Stick Pin, of which the following is a specification, reference being had to the accompanying drawing, forming a part thereof.

The drawing shows an elevation.

We claim—

The ornamental design for a hat or stick pin as shown.

GEO. M. MEREDITH.

JAQUELIN M. MEREDITH, JR.

Witnesses:

WALTER B. BURROW,

V. S. BURROW.
